Playology Squeaky Chew Ball Dog Toy, for Large Dogs Beef Large Bounce Ball, posted Feb. 24, 2021 [online], [retrieved Dec. 28, 2022]. Retrieved from internet <https://www.amazon.com/dp/B08XC5GPVL?th=1> (Year: 2021).*

Primary Examiner — Sheryl Lane*Assistant Examiner* — Emily A Caven(74) *Attorney, Agent, or Firm* — Hansen IP Law PLLC(57) **CLAIM**

The ornamental design for a pet bounce ball, as shown and described.

DESCRIPTION

FIG. 1 is a perspective view of a pet bounce ball showing my new design;

FIG. 2 is a first side elevational view of the pet bounce ball of FIG. 1;

FIG. 3 is a second side elevational view of the pet bounce ball of FIG. 1, the second side elevational view being opposite the first side elevational view;

FIG. 4 is a third side elevational view of the pet bounce ball of FIG. 1;

FIG. 5 is a fourth side elevational view of the pet bounce ball of FIG. 1, the fourth side elevational view being opposite the third side elevational view;

FIG. 6 is a top plan view of the pet bounce ball of FIG. 1; and,

FIG. 7 is a bottom plan view of the pet bounce ball of FIG. 1.

The broken lines in the drawings depict portions of the pet bounce ball that form no part of the claimed design.
